DIRECT CURRENT TRANSFORMER

Filed Dec. 20, 1946

FIG. 2.

FIG. I.

UNITED STATES PATENT OFFICE

2,467,840

DIRECT-CURRENT TRANSFORMER

George E. Mallineckrodt, St. Louis, Mo.

Application December 20, 1946, Serial No. 717,521

7 Claims. (Cl. 323—27)

1

This invention relates to transformers, and with regard to certain more specific features, to step-down transformers for direct current.

Among the several objects of the invention may be noted the provision of apparatus for transforming direct current of one voltage into direct current of another voltage; the provision of a transformer of the class described which involves no make-and-break systems either of the vibrating contact or oscillating circuit varieties; the provision of a transformer of this class which will safely handle a supply circuit potential of relatively high value and provide a relatively large step-down ratio to a work circuit potential of lower values; and the provision of a simple and economical transformer of this class which will remain reliable throughout a substantial life. Other objects will be in part apparent and in part pointed out hereinafter.

The invention accordingly comprises the elements and combinations of elements, features of construction and arrangements of parts which will be exemplified in the structures hereinafter described, and the scope of the application of which will be indicated in the following claims.

In the accompanying drawings, in which one of various possible embodiments of the invention is illustrated,

Fig. 1 is a diagrammatic layout of the invention, being taken on line 1—1 of Fig. 2; and

Fig. 2 is a horizontal section taken on line 2—2 of Fig. 1.

Similar reference characters indicate corresponding parts throughout the several views of the drawings.

Referring to the drawings, there is shown at numeral 1 a highly evacuated and hermetically sealed envelope or manifold which may be composed of any suitable material for the purpose, such as, for example, heat-resistant glass tubing such as "Pyrex," of about 3 in. bore. Within an indented end 5 of this envelope is located a cathode 3 which is heated to electron emissivity by means of a heater circuit 24, supplied by means of a 6 v. battery 7, for example.

At numeral 9 is shown a control grid which may be either negatively or positively biased by means of a control circuit 11, including a 0-10 v. battery 13, for example.

At the other end of the envelope 1 is an anode 15. The cathode 3 and the anode 15 are in a high-potential D. C. primary supply circuit 17. This circuit is supplied from a high-potential D. C. source (not shown) of 100,000 v., for example. The anode 15 constitutes a relatively

2

thick end closure composed, for example, of steel of about 4 in. diameter and about $\frac{1}{2}$ in. thick. The glass tube 1 is flanged at 19, underneath which it is ground and lap-fitted to the face of the anode 15. It is held down by means of a clamp ring 22, the latter being fastened by studs 26 threaded into the anode 15. Grease or other sealing compound in the lap-joint thus formed provides an hermetic seal. Air is exhausted from the tube 1 by means of an exhaust port 2 connected with a suction line 4 which is welded to the anode at collar 6.

Between the anode 15 and the cathode 3 is a relatively thin partition or shield 21, composed, for example, of a thin foil of beryllium approximately .0025 in. thick or aluminum approximately .002 in. thick. This is located about 2 cm. from the inner surface of the anode 15 and is only slightly less in diameter than the bore of tube 1. The partition 21 is in the desired secondary low-potential D. C. load or work circuit 23.

Mounting of the partition foil 21 is accomplished by providing three glass insulators 8A, 8B and 8C affixed in holes through the anode 15. These insulators support a conducting ring 10 to which the foil 21 is peripherally attached. Through one insulator 8A passes a return lead from the secondary circuit 23. This is connected to ring 10. Through part of insulator 8B passes a lead from a negative grid bias circuit 12 to a suppressor grid 14 close to the inner surface of anode 15. The grid circuit 12 is supplied by means of a 45 v. battery 28, for example. Insulator 8C functions only as a third support for the ring 10 of partition 21. In order hermetically to seal the insulators, each is fused to a glass nipple 16 into which is fused its respective lead and which in turn is fused to an alloy collar 18. Each collar is in turn soldered to the outside of the anode 15. Such hermetic sealing constructions are common and further detailed description is therefore unnecessary.

The distance from the foil 21 to the cathode 3 is of the order of 9 inches and may be as low as 1 inch. The length of the indentation 5, for proper insulation, is of the order of 2 feet. The dimensions hereinbefore given are for the stated 100,000 v. potential in the primary circuit 17 and for a 5,000 v. to 10,000 v. potential in the secondary circuit 23. In view of the above, there will be a potential field gradient throughout the 9-in. distance between the cathode 3 and the anode 15. The total value is 100,000 v., tending to drive or accelerate toward the anode 15 electrons emitted from the cathode 3. These

electrons will have their maximum energy in the vicinity of the anode 15, which, as will be seen, is the reason for placing the partition 21 close to said anode 15.

Operation is as follows, referring to a primary electron (negative charge) driven from the cathode 3. Because anode 15 is always positive relatively to the cathode 3, as indicated by the solid plus and minus signs thereon, this primary electron is driven as suggested by the line of 10 arrows 33 and arrives with near maximum energy of approximately 100,000 electron volts at the foil 21. Here it dislodges a multiplicity of secondary electrons (negative charges) which under the ratio of 100,000 v. to say, 5,000 v. in secondary 15 23, will be of the order of twenty electrons (maximum). This is suggested by the fan-shaped group of arrows 35. The foil at this time is relatively minus with respect to the anode 15, since it lies between it and the cathode 3. This is indicated by a solid minus sign on the side of the secondary circuit 23 connected with the foil 21. (If the secondary potential is to be 10,000 v., then the number of electrons dislodged will be ten, maximum.) The twenty released electrons are driven from the thin foil 21 toward the thick anode 15.

Thus, under the assumed starting conditions the anode 15 will initially be relatively positive with respect to the foil 21, and these conditions are shown by the solid plus and minus signs, as stated. The reason for this stated sense of initial polarities is the direction of the field potential gradient in the envelope 1 when no current is flowing in the apparatus.

The twenty electrons arrive at the anode 15 and immediately build up thereon a negative charge (as suggested by the dotted minus sign) to the extent of reversing the polarity of the secondary load circuit 23, as indicated by the 40 dotted plus sign on said secondary circuit.

Under these conditions the anode 15 is still positive relatively to the cathode 3. But under the operating conditions the anode 15 is relatively negative with respect to the foil 21 and that only is what said dotted plus and minus signs indicate.

Although the secondary electrons 35 bombard the anode 15, its thickness prevents the dislodgment of any more electrons, except possibly a few stray ones on its inner surface which are driven back by means of the suppressor grid 14, that being the purpose of this grid. That is, this anode is substantially non-emissive.

In view of the above, it will be clear that the operating polarities of the load circuit 23 are the reverse of its initial polarities under starting conditions. This, so far as circuit 23 is concerned, results in a potential gradient between the anode 15 and foil 21 which is inverse to the potential gradient in circuit 17 between the cathode 3 and the anode 15. Thus operating conditions of the primary circuit and of the load circuit are established and maintained.

Regarding the voltage to be maintained in the load circuit 23, this will preferably be such as will allow an optimum number of the secondary electrons 35 to reach the anode 15. This, under the conditions to be maintained in the case of the present example, will be something between ten and twenty per primary electron striking the foil. The conditions to be maintained will be clear when it is noted that the number of electrons dislodged from the thin foil 21 is constant for a given voltage and current in the primary circuit 17 and for a given foil thickness. These secondary electrons

represent the available current which may be drawn upon by the secondary circuit 23. But if little or no negative charge were built up on the anode 15, most or all of the secondary electrons 35 would strike it without substantial resistance against their flow, which would result in a relatively low potential in the circuit 23. This would also result in excessive heating of the anode 15 and perhaps its destruction, due to the secondary electrons striking it with full velocity and energy. Thus the voltage of the load circuit 23 cannot be reduced indefinitely. On the other hand, if the negative charge on the anode 15 is allowed to build up too high a value, all flow of secondary electrons 35 will be stopped and the action of the transformer will cease. Under such conditions there is also danger of overheating the foil 21 by reason of forcing back to it too many of the electrons 35. The operating voltage value of the load circuit 23 should therefore be carried at a value which will produce neither of said limiting conditions.

The minimum heating of anode 15 and maximum power from the secondary circuit are obtained by operating the secondary circuit at as high a voltage as possible, above which the current would drastically drop, due to the inverse potential field forcing back too many of the electrons 35, and above which there would be the stated danger of forcing back too many of the electrons into the thin foil 21. By operating at said maximum power there is avoided the possibility that by reducing the voltage too much in the load circuit, there may not be enough inverse field applied against the oncoming electrons to slow them down sufficiently to prevent overheating of the thick anode 15. Since power is a product of volts and amperes, if the voltage were reduced too much the electric power in circuit 23 would also be reduced, and this reduction in electric power would manifest itself as undesirable heat in the anode 15. Thus the maximum power to be withdrawn in the secondary circuit is determined by said desirable voltage maintained in the secondary circuit which lies somewhere between the above-mentioned two limits (between 5,000 v. and 10,000 v.) in the present example.

Thus it may be seen that the secondary circuit, including all apparatus therein, must have impedance-current drop equal to the above-mentioned optimum operating voltage, or, $IZ=V$, which may lie between 5,000 v. and 10,000 v. The circuit load and impedance is designed for this result.

The above description is in terms of one primary electron emitted from the cathode 3, but it will be understood that the action is on an average the same for each electron emitted, and that the number of electrons subject to the operation described is a function of the amperes flowing in the primary circuit 17.

Returning to the characteristics of the thin foil or shield 21, its thickness depends upon (1) the desired step-down ratio, and (2) the voltage in the primary circuit.

Regarding the factor (1) of the step-down ratio, assuming a given primary voltage, the thicker the coil the higher will be the step-down ratio. Thus, for example, if it were desired to change the voltage ratio from 100,000 v. to 2,000 v. (instead of the stated 100,000 v. to between 5,000 v. and 10,000 v.), the aluminum foil thickness would need to be greater than the stated .002 inch. As another example, if it were desired to step down 2,000,000 primary volts to

between 10,000 and 15,000 secondary volts, the thickness of the foil might be greater than approximately .2 in. of aluminum.

Regarding the factor (2) of the voltage in the primary, the thickness of the foil for a given secondary voltage is a function of the primary voltage. As an example, for a primary voltage of approximately 1,000,000 to be stepped down to approximately 5,000 to 10,000, approximately .1 in. of aluminum foil thickness might be required.

As to the vacuum to be maintained in the envelope 1, this should be good enough to permit efficient electron flow in the tube and to establish adequate vacuum dielectric strength; but it will be understood that if a known, so-called cold cathode is used, some gas may be introduced.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. An electric D. C. transformer comprising an electron tube having an emissive cathode and a substantially non-emissive anode in a relatively high-voltage D. C. circuit, an emissive shield in said tube between the cathode and the anode adapted to be bombarded on one side by primary electrons moving from the cathode toward the anode, said shield emitting under said bombardment multiple electrons on its other side toward the anode, said shield and anode being connected into a D. C. work circuit.

2. An electric D. C. transformer comprising an electron tube having an electron-emissive cathode and a substantially non-emissive anode, both in a relatively high-voltage D. C. circuit, said anode being relatively positive with respect

to the cathode, an emissive shield in said tube between the cathode and the anode positioned to be bombarded on its side adjacent the cathode by primary electrons from the latter and being thin enough to emit secondary electrons on its side adjacent the anode to build an electron charge on the latter which becomes relatively negative with respect to said shield, said shield and anode being connected to a relatively low-voltage D. C. work circuit supplied by secondary electrons under the electron voltage which exists between the anode and the shield.

3. Apparatus made according to claim 2 in which said shield is composed of a solid sheet of aluminum of the order of several thousandths of an inch thick.

4. Apparatus made according to claim 2 in which said shield is made of a solid sheet of beryllium of the order of several thousandths of an inch thick.

5. Apparatus made according to claim 2 in which said tube includes a control grid for the cathode.

6. Apparatus made according to claim 2 in which said tube includes a suppressor grid for the anode.

7. Apparatus made according to claim 2 in which said tube includes a control grid for the cathode and a suppressor grid for the anode.

GEORGE E. MALLINCKRODT.
